(57) **CLAIM**

The ornamental design for a toy vehicle, as shown and described.

DESCRIPTION

FIG. 1 is an upper/left/front perspective view of a toy vehicle in accordance with our new design;

FIG. 2 is a left side elevation view thereof, the right side elevation being a mirror image;

FIG. 3 is a top plan view thereof;

FIG. 4 is a bottom plan view thereof;

FIG. 5 is a front elevation view thereof; and,

FIG. 6 is a rear elevation view thereof.

The lettering on the tires is not part of the claimed design.
